UNITED STATES PATENT OFFICE.

JAMES J. BYRNE, OF BUFFALO, NEW YORK.

STARTING DEVICE.

1,094,056.

Specification of Letters Patent. Patented Apr. 21, 1914.

Application filed October 15, 1912. Serial No. 725,822.

To all whom it may concern:

Be it known that I, JAMES J. BYRNE, a citizen of the United States, residing at Buffalo, in the county of Erie and State of New York, have invented a new and useful Improvement in Starting Devices, of which the following is a specification.

This invention relates to starting or cranking devices for internal combustion engines of the kind which are provided with means for preventing the reverse motion of the engine, due to "back firing," from being transmitted to the starting crank.

The objects of the invention are to produce a device of this kind of novel construction which is thoroughly reliable in operation and which will absolutely eliminate the danger of injury to the operator from the back firing of the engine; also to produce a device of this kind which can be readily adapted to operation by power driven means; also to adapt the device to be readily disconnected from the engine shaft when the engine is in operation, and to be automatically connected with the engine shaft for starting the engine; also to improve the construction of devices of this kind in the respects hereinafter specified.

In the accompanying drawings, consisting of three sheets: Figure 1 is a front elevation of a starting device embodying the invention. Figs. 2 and 3 are respectively a plan view and a side elevation thereof, on an enlarged scale. Figs. 4 and 5 are sectional elevations thereof on line 4—4, Fig. 2, showing the parts of the device in different positions. Fig. 6 is a similar sectional elevation of a starting device of slightly modified construction. Fig. 7 is a sectional elevation of the starting device shown in Figs. 1—5, on line 7—7, Fig. 2. Fig. 8 is a fragmentary sectional elevation of the ratchet gear, on line 8—8, Fig. 2. Fig. 9 is a section thereof on line 9—9, Fig. 8. Fig. 10 is a fragmentary sectional elevation similar to Figs. 4 and 5 showing the parts in a different position. Fig. 11 is a sectional elevation of a compressed air starting device.

Like reference characters refer to like parts in the several figures.

The starting device comprises a train of gears mounted on a suitable frame and adapted to transmit motion from a starting crank to the engine shaft. One of the gears of the train is journaled on a pivoted

arm which is operatively connected with one of the gears of the train in such a manner that the reverse movement of the train of gears, caused by the back firing of the engine, will swing the arm on its pivot and throw the gear carried thereby out of mesh with the coöperating gear and thereby prevent the reverse motion from being transmitted to the starting crank.

The parts of the device are preferably mounted in a suitable frame or casing which, in the construction shown, comprises front and back plates A A' rigidly connected by bolts *a* surrounded by spacing sleeves *a'*.

B represents the cranking or starting shaft of the device which is journaled in the two plates A A' of the frame and is provided with a hand crank *b* for turning it, and C represents the engine or driven shaft, which may be either the crank shaft of the engine or a separate shaft suitably connected therewith. A gear D is rigidly secured on the shaft B and meshes with a gear E which is suitably journaled, preferably on a stud shaft *d* secured to the back plate A' of the frame.

The gear E is connected with a second gear E' by any suitable ratchet or clutch mechanism adapting the gear E' to be turned by the gear E in one direction and to turn in the same direction independently of the gear E. In the construction shown, see Figs. 8 and 9, the gear E is rigidly secured to a sleeve *e*, which is journaled on the stud shaft *d* and is provided with a number of radial pockets containing gravity pawls *e'* adapted to engage with corresponding teeth or projections *e''* formed on the gear E'. Any other ratchet connection may be used between the engine shaft C and the starting shaft B to prevent the forward movement of the engine from being transmitted to the crank *b*.

The gear E' meshes with an idler gear F, suitably journaled, for instance, by a pin *f* on an arm *f'* which is pivoted at *f''* preferably on the plate A of the frame, concentric with the gear E' so that the idler gear F is adapted to swing about the gear E'. The gear F is adapted to be moved into and out of mesh with a gear G, rigidly secured to the engine driven shaft C. The means employed for automatically throwing the idler gear F out of mesh with the gear G in the event that the engine back-fires, pref.

erably comprise a lever H, Figs. 2-5, 7 and 10, which is pivoted at h on the front plate A of the frame. One end of this lever engages the journal pin f or other part on the free end of the arm f' , and is adapted to raise the end of the arm and throw the gear F out of mesh with the gear G when the lever is swung on its pivot. At its other end the lever is provided with a suitable yielding pawl or detent h' arranged to engage the teeth of the gear wheel E'. The pawl shown, see Fig. 7, consists of a sliding spring-actuated plunger confined in a pocket h^2 on the lever H and having a beveled end enabling the pawl to ride over the teeth of the gear E' when the gear is being turned by the engine while running forwardly. When, however, this gear is turned in the opposite direction, the pawl engages with the gear teeth and is drawn downwardly, thereby swinging the lever H on its pivot and raising the idler gear F out of mesh with the gear G, as shown in Fig. 5, thus preventing the reverse movement of the engine from being transmitted to the starting crank b .

In the modified construction shown in Fig. 6, the lever H and arm f' are replaced by a single lever I, pivoted at i concentrically with the gears E and E' and having the idler gear F mounted on one end thereof and a spring-actuated detent i' at the other, and which co-operates with the gear E' for swinging the lever I to throw the idler gear F out of mesh with the gear G in the same manner as the detent h' before described. This construction is simpler and involves fewer parts than the construction shown in Figs. 1-5, 7 and 10, but the latter construction gives a greater leverage for lifting the idler gear F out of mesh with the gear G.

In the operation of the device, when the starting crank is turned in the direction for driving the engine forwardly, the friction between the gear E and the pawl engaging with the teeth thereof, together with the weight of the idler gear F, will tend to turn the arm f' (or the lever I when this is used) downwardly to place the idler gear in mesh with the gear G, as shown in Figs. 4 and 7. This tendency will be greater as the turning effort increases, so that a good engagement between the gears is insured. When the engine starts, the ratchet mechanism permits the gear E' to turn freely relatively to the gear E, so that the movement of the engine is not transmitted to the starting crank.

Means are preferably provided for moving the idler gear out of engagement with the gear G after the engine has been started. In the construction shown, this is accomplished by means of a cam or disk K, pivoted at k on the frame of the device and adapted to co-operate with a part or extension k' of the arm f' . The disk shown is substantially

circular with a flat peripheral portion k^2 and has a handle k^3 for turning it. When the disk is turned so that the flat portion is adjacent to the extension of the arm f' , see Fig. 4, the arm is free to swing in the direction to place the idler gear in mesh with the gear G. When the disk is turned by moving the handle k^3 to the right in Figs. 1, 4, 5, 6 and 9 so that the circular part of the disk engages the extension k' of the arm f' , Fig. 9, it will swing this part of the arm downwardly, thus raising the idler gear F out of mesh with the gear G. The starting mechanism can be again connected with the engine shaft by moving the handle k^3 back so that the flat face is parallel with the extension k' of the arm. Means are, however, preferably employed whereby the disk K will be turned to permit the idler gear to mesh with the gear G by the turning of the crank b for starting the engine. This is accomplished, in the construction shown, by providing an arm L which is pivoted concentric with the disk K and the end of which is connected by a link l' to the end of the lever H. The arm is adapted to strike a pin l^3 on the disk K. When the crank b is turned to start the engine, the detent h' will swing the lever H on its axis and thus raise the link l' and swing the arm L so that the arm will strike the pin l^3 of the disk K and turn the disk to permit the arm f' to swing the idler gear F into mesh with the gear G.

The described mechanism readily lends itself to be operated by a suitable power device to form a self-starting mechanism. For example, in the construction shown in Fig. 11 the crank b on the shaft B is replaced by a pinion M which engages with a rack m which can be reciprocated by any suitable power-actuated means. When the rack is moved so as to turn the gear M in the direction for starting the engine, this motion will be transmitted to the engine shaft as heretofore described, and in case of back firing, the reverse motion of the engine will not be transmitted to the gear M. When the gear is rotated in the reverse direction by the return movement of the rack, this motion will not be transmitted to the engine shaft owing to the ratchet connection between the gears E and E'.

In the construction shown, the rack m is formed on or connected to a piston N, which has a central slot n through which the shaft B projects. The piston is adapted to be reciprocated in a cylinder n' , which may be of any desired construction, being provided at its opposite sides with inlet ports controlled by a suitable valve (not shown) for the admission of air or gas under pressure, and with outlet ports which are uncovered by the piston at the opposite ends of its stroke to permit the actuating fluid to be discharged from the piston.

I claim as my invention:

1. In a starting device for internal combustion engines, the combination with an engine driven shaft and a starting shaft, of a train of gears connecting said shafts, one of said gears being movable into and out of operative relation to a coöperating gear, a pivoted lever, and means secured to one arm of said lever which are adapted to engage one of said gears, the other arm of said lever engaging said movable gear, whereby the reverse movement of said train of gears swings said lever about its pivot to move said movable gear out of operative position, substantially as set forth.

2. In a starting device for internal combustion engines, the combination with an engine driven shaft and a starting shaft, of a train of gears connecting said shafts, one of said gears being movable into and out of operative relation to a coöperating gear, a casing in which said gears are mounted, a lever pivoted on said casing and adapted to move said movable gear into and out of operative relation with said coöperating gear, and means operated by the reverse movement of the train of gears to swing said lever on its pivot to move said movable gear out of mesh with its coöperating gear, substantially as set forth.

3. In a starting device for internal combustion engines, the combination with an engine driven shaft and a starting shaft, of a train of gears connecting said shafts, a ratchet mechanism between two gears of the train which permits said engine driven shaft to turn in a forward direction independently of said starting shaft, one of the gears of said train being journaled on a pivoted member, and means actuated by the reverse movement of the gears for swinging said pivoted member to move the gear thereon out of mesh with its coöperating gear, substantially as set forth.

4. In a starting device for internal combustion engines, the combination with an engine driven shaft and a starting shaft, of a train of gears connecting said shafts, a pivoted member on which one of the gears of the train is journaled, and which is adapted to swing about its pivot to move the gear mounted therein into and out of mesh with a coöperating gear, and a lever adapted to be actuated by the reverse movement of said train of gears to swing said member to cause the gear mounted thereon to be moved out of mesh with its coöperating gear, substantially as set forth.

5. In a starting device for internal combustion engines, the combination with an engine driven shaft and a starting shaft, of a train of gears connecting said shafts, a pivoted member on which one of the gears of the train is journaled, and which is adapted to swing about its pivot to move the gear

mounted therein into and out of mesh with a coöperating gear, a lever, a pawl at one end of said lever which is adapted to engage with the teeth of one of the gears of said train when said gear turns in the reverse direction, whereby the lever is swung on its pivot to swing said member to cause the gear mounted thereon to move out of mesh with its coöperating gear, substantially as set forth.

6. In a starting device for internal combustion engines, the combination with an engine driven shaft and a starting shaft, of a train of gears connecting said shafts, one of said gears being movable into and out of operative relation to a coöperating gear, a pivoted lever, and means secured to one arm of said lever which are adapted to engage one of said gears, the other arm of said lever engaging said movable gear, whereby the reverse movement of said train of gears swings said lever about its pivot to move said movable gear out of operative position, and means for holding said movable gear out of mesh with its coöperating gear when the engine is running, substantially as set forth.

7. In a starting device for internal combustion engines, the combination with an engine driven shaft and a starting shaft, of a train of gears connecting said shafts, a ratchet mechanism between two gears of the train which permits said engine driven shaft to turn in a forward direction independently of said starting shaft, a pivoted member on which one of the gears of said train is journaled, means actuated by the reverse movement of the gears for swinging said pivoted member to move the gear thereon out of mesh with its coöperating gear, and a cam adapted to engage said member to swing the same to move the gear journaled thereon out of mesh with its coöperating gear when the engine is running, substantially as set forth.

8. In a starting device for internal combustion engines, the combination with an engine driven shaft and a starting shaft, of a train of gears connecting said shafts, a pivoted member on which one of the gears of the train is journaled, a lever adapted to be actuated by the reverse movement of said train of gears to swing said member to cause the gear mounted thereon to be moved out of mesh with its coöperating gear, a cam adapted to engage said member to swing the same to move the gear journaled thereon out of mesh with its coöperating gear when the engine is running, and connections between said lever and said cam for causing said cam to release said member when said starting shaft is turned, substantially as set forth.

9. In a starting device for internal combustion engines, the combination with an

engine driven shaft and a starting shaft, of a train of gears connecting said shafts, one of said gears being movable into and out of operative relation with a coöperating gear, a lever for thus moving said movable gear, means operated by the reverse movement of said train of gears to actuate said lever to move said gear out of operative position, a ratchet mechanism between two gears of the train, a gear on said starting shaft, a rack with which said gear engages, and which is adapted to be reciprocated for turning said gear on said starting shaft, substantially as set forth.

10 10. In a starting device for internal combustion engines, the combination with an engine driven shaft and a starting shaft, of a train of gears connecting said shafts, one of said gears being movable into and out of

operative relation with a coöperating gear, 20 a lever for thus moving said movable gear, means operated by the reverse movement of said train of gears to actuate said lever to move said gear out of operative position, a ratchet mechanism between two gears of the 25 train, a gear on said starting shaft, a rack with which said gear engages, said rack being secured to a piston, and a cylinder in which said piston is adapted to reciprocate to turn said gear for starting the engine, 30 substantially as set forth.

Witness my hand, this 11th day of October, 1912.

JAMES J. BYRNE.
